CLAIM

(22) Filed: **Jan. 31, 2019**

An ornamental design for a display screen with graphical user interface for a timeline-video relationship presentation for alert events, as shown and described.

Related U.S. Application Data

(63) Continuation of application No. 29/582,305, filed on Oct. 26, 2016, now Pat. No. Des. 843,398.

DESCRIPTION

(51) **LOC (12) Cl.** **14-04**

This application is related to the following applications, which are all incorporated by reference in their entirety: U.S. patent application Ser. No. 15/335,399, titled “Timeline-Video Relationship Presentation for Alert Events,” filed Oct. 26, 2016; and

(52) **U.S. Cl.** **D14/486**

U.S. patent application Ser. No. 15/335,396, titled “Timeline-Video Relationship Processing for Alert Events,” filed Oct. 26, 2016.

(58) **Field of Classification Search**

The FIGURE is a front view of a display screen with graphical user interface for a timeline-video relationship presentation for alert events, showing our new design.

USPC ..... D14/485—495

The broken lines showing a portion of a display screen, text, and other elements in the FIGURE are for illustrative purposes only and form no part of the claimed design.
